UNITED STATES PATENT OFFICE.

ARTHUR S. HUNTINGTON, OF OMAHA, NEBRASKA.

DESIGN FOR A LEGGING.

SPECIFICATION forming part of Design No. 29,205, dated August 9, 1898.

Application filed March 2, 1898. Serial No. 672,332. Term of patent 7 years.

To all whom it may concern:

Be it known that I, ARTHUR S. HUNTINGTON, of Omaha, in the county of Douglas and State of Nebraska, have invented and produced a new and original Design for a Legging, of which the following is a full, clear, and exact specification.

Reference is to be had to the accompanying drawings, forming a part of this specification, in which similar characters of reference indicate corresponding parts in all the figures.

Figure 1 is a side elevation of a legging, showing the design. Fig. 2 is an enlarged perspective view of part of the legging with one of the flaps turned over to show the design. Fig. 3 is a rear elevation of the lower portion of the legging, and Fig. 4 is a sectional side elevation of the legging.

The leading feature of the design consists

of the stiffening-band parts A A', approximately semicircular in shape and arranged on the inner and outer faces of the heel portion of the legging opposite each other, the said band parts appearing as raised and the bases thereof being embraced by the binding-strip B at the lower end of the legging.

The legging, except as hereinbefore set forth, is of the ordinary construction and is provided with the usual side fastenings and instep-strap.

I claim—

The design for a legging, as herein shown and described.

ARTHUR S. HUNTINGTON.
